(57) **CLAIM**

The ornamental design for a unitary swivel, as shown and described.

DESCRIPTION

FIG. 1 is a front perspective view of a first embodiment of a unitary swivel with a lid on the top of the seat and without the cross cutout on the bottom of the seat.

FIG. 2 is a rear perspective view thereof.

FIG. 3 is a top view thereof.

FIG. 4 is a bottom view thereof, showing the cross-section location of FIGS. 5 and 6.

FIG. 5 is a left cross section view thereof.

FIG. 6 is a right cross section view thereof.

FIG. 7 is a left side view thereof.

FIG. 8 is a right side view thereof.

FIG. 9 is a front view thereof.

FIG. 10 is a rear view thereof.

FIG. 11 is a front perspective view of a second embodiment of a unitary swivel with a lid on the top of the seat and with the cross cutout on the bottom of the seat.

FIG. 12 is a rear perspective view thereof.

FIG. 13 is a top view thereof.

FIG. 14 is a bottom view thereof, showing the cross section location of FIGS. 15 and 16.

FIG. 15 is a left cross section view thereof.

FIG. 16 is a right cross section view thereof.

FIG. 17 is a left side view thereof.

FIG. 18 is a right side view thereof.

FIG. 19 is a front view thereof; and,

FIG. 20 is a rear view thereof.

The illustrative broken lines depict environmental subject matter that form no part of the present claimed design.

FIGS. 3-10 and 13-20 are shown in enlarged scale, without environmental structure for ease of illustration.

1 Claim, 14 Drawing Sheets
